ART OF AND APPARATUS FOR COOLING AND CONDENSING GASOLENE OR LIGHT VAPORS,
APPLICATION FILED JULY 2, 1919.

1,340,427.

Patented May 18, 1920.

UNITED STATES PATENT OFFICE.

AUSTIN A. WEHR, OF BADEN, PENNSYLVANIA.

ART OF AND APPARATUS FOR COOLING AND CONDENSING GASOLENE OR LIGHT VAPORS.

1,340,427.

Specification of Letters Patent. Patented May 18, 1920.

Application filed July 2, 1919. Serial No. 308,098.

To all whom it may concern:

Be it known that I, AUSTIN A. WEHR, a citizen of the United States, residing at Baden, in the county of Beaver and State of Pennsylvania, have invented certain new and useful Improvements in Art of and Apparatus for Cooling and Condensing Gasolene or Light Vapors, of which the following is a specification, reference being had to the accompanying drawings.

10 Natural gas frequently carries light oils, particularly gasolene and hydrocarbons of the same group, and this invention relates to the separating of the light oils or gasolene from this gas.

15 In the processes commonly employed for this purpose, high pressures are used in the condensers that are employed, and the use of these high pressures is open to many objections.

20 One of the objects of the present invention is to provide a system of condensing and cooling the gas by which a relatively low pressure of, say 125 pounds, may be used instead of using the ordinary pressure of 25 250 pounds, thus doing away not only with the danger of using these extremely high pressures, but as a matter of fact permitting the collection of a greater amount of the 30 light hydrocarbons than is possible by the old methods in use at the present time.

A further object of my invention is to 35 provide an apparatus for the purpose described so constructed that a certain amount of gas and gasolene under a relatively high pressure is suddenly expanded in a freezing chamber, this sudden expansion, of course, greatly reducing the temperature within the chamber, the apparatus being further so 40 constructed as to provide cooling coils within the chamber through which gas to be cooled is passed, thus causing a great cooling and condensation of this gas, this cooled and condensed gas being thence passed into 45 an accumulating tank where the liquid is accumulated and the remaining vapor drawn off to be further acted upon.

A further object is to provide a construction whereby all of the gasolene held in 50 storage may be kept under freezing temperature, thus preventing evaporation of the liquid gasolene.

55 A further object is to provide a mechanism to the end described which is very cheap, easy to handle, and comprises ma-

chinery ordinarily found in all gasolene plants, thus doing away with the necessity of installing any extra machinery.

My invention is illustrated in the accompanying drawings, wherein:

60 The figure is a diagrammatic sectional view of my apparatus.

In this drawing I have illustrated diagrammatically a pipe 10 leading from a compressor 11, this compressor being of the usual type and leading into the top of an accumulator tank 12. There is the usual vacuum line 9 leading from the well to the compressor, and the pipe 10 is to be surrounded between the compressor 11 and the 70 tank 12 with a cooling coil shown conventionally in the drawing and designated 10^a. Leading from the lower portion of the tank 12 is a pipe 13 which extends upward through the top of the tank and is there 75 connected to a pipe 14 having in its length a cut off valve 15. This pipe 14 opens into a cooler 16 comprising a cylindrical, hollow shell having any desired length and being many times the diameter of the pipe 14. 80 From the opposite end of this shell or cooler 16 extends a pipe 17 which leads into a stock tank 18, from which the air has been exhausted.

Leading from the upper end of the tank 85 12 and passing through a stuffing box 19 in the end of the cylinder 16 is a pipe 20 which extends longitudinally through the tank 16 and is bent upon itself a plurality of times, and which eventually passes out through a 90 stuffing box 21 in the cylinder 16, and from thence leads, as by the pipe 22, to the main accumulating tank 23, into the top of which the pipe 22 discharges. From the top of 95 this tank 23 leads a pipe 24, from which dry gas may be taken for power after the gasolene has been taken from the gas, in other words the tanks 12 and 23 act as separators separating the liquid gasolene condensed from the gas, leaving dry gas.

100 In tank 23 all the gasolene is separated from the dry gas. The dry gas passes through the line 24 to be used for power, but the gasolene is transferred through pipe line 25 to the stock tank 18 and there kept under freezing temperature. This is caused by the release of gasolene from tank 12 through lines 13 and 14 into the cooler 16 105 by pipe 17 to the stock tank 18 which is kept under a vacuum by the pipe line 26 and 110

which extends from the tank 18 back to line 9.

In the stock tank 18 all the gasolene is collected that is made by the cooling coils 5 and the floating vapors that escape with the gasolene from tank 12 are returned to the compressor by the line 26, there to be compressed, and recooled and the gasolene extracted.

- 10 It is to be understood that the construction which I have illustrated in the drawing is diagrammatically shown, and that I have not attempted to illustrate all the details of an installation of this character, as 15 it is obvious that these details will be modified in different ways by the exigencies of any particular situation. The general operation of the mechanism will be obvious to those skilled in the art. The valve 15 is intended to be only partly opened, and in 20 this case the vacuum in the stock tank 18 causes gas and gasolene to be taken from the first accumulator tank 12 under a relatively high pressure, and this gas and gasolene 25 expanding within the relatively large tank or cylinder 16 causes a freezing temperature to be produced within this cylinder 16. Assuming that the vapor is very highly compressed, as for instance, has a 30 pressure of 125 pounds to the square inch when it passes into the first collection tank 12, this pressure is reduced to about 5 pounds or as low a pressure as can be obtained. The dry gas leaves the first collection 35 tank 12 by means of the pipe 20 and in its circuitous course through the cooler 16, this dry gas is cooled or frozen, the gasolene condensed, and the gasolene is discharged into the accumulating tank 23. 40 while the remaining gas is taken off by the pipe 24 to be otherwise used. It will be understood that the tank 12 is to be surrounded by some cooling agent, as for instance, cooling coils or water so that a certain 45 amount of the gasolene is collected in the tank 12 and a further and greater condensation is produced in the cooler 16 so as to cause the discharge of the liquid gasolene into the accumulating tank 23. 50 It will be seen that the apparatus which I have devised for this purpose is very simple and such as is ordinarily found in gasolene manufacturing plants, but that by allowing the highly compressed vapor and 55 gasolene to expand within the relatively large chamber or cylinder 16, that I secure an intense cold which will cause the condensation of the gasolene and its precipitation in tank 23. A far greater condensation 60 is produced by passing the relatively dry gas through the tank 16 and submitting it to the intense cold therein than can possibly be produced by cooling it by water or compressed air. In actual practice, I find 65 that by using my cooler I can abstract as

much gasolene at 125 pounds pressure as can be abstracted by the old method at 250 pounds pressure. Furthermore, I can collect a greater amount of the light hydrocarbons than is possible by methods in use 70 at the present time, and more than this, I eliminate the great danger which is present where extreme high pressures are used. Again, I can keep all of the gasolene so made in storage under freezing temperature 75 and this saves loss by evaporation, as it will be obvious as soon as compressed gasolene comes to a temperature of from 44° to 48° F., it starts to boil and evaporate.

It will be understood, of course, that the 80 greater the vacuum, the greater is the freezing inside of the cooler 16, and also the cooler the gasolene in the storage tank will be. All of the frozen gasolene is carried 85 into the stock tank and a continuous flow through the cooler into the stock tank of frozen gasolene and gas keeps the gasolene in the stock tank frozen at all times.

It is to be noted that with my construction I entirely do away with the necessity 90 of using compressed air, and thus do away with the necessity of installing machinery separate from the gasolene compressor. The installation of air compressing machinery is very expensive and means much more 95 wear and tear on the fuel mechanism. Furthermore, air is not successful unless ammonia is used, and this is a great expense. Further, it is difficult to keep the air compressing mechanism in proper working 100 order and the action of ammonia on the coils soon eats them up, unless copper coils are installed, and this is very expensive. With my mechanism, one machine does all 105 the work and it is only necessary to regulate the valve 15, and this ordinarily does not have to be touched for a week at a time. The tank 12 in actual practice will be 24' by 36', and tank 23 will be 36' by 96'. The storage tank 18 will hold ordinarily a 110 thousand gallons. It will be obvious from these dimensions that the drawing is purely diagrammatic in character.

As before remarked, I do not wish to be limited to the particular mechanism shown, 115 as this is purely illustrative of the type of apparatus which I design to use and the method by which I secure the condensation of the gas.

I claim:—

1. In the art of producing gasolene and light oils from vapor, a step which consists in compressing the vapor in an accumulator chamber and thereby separating a certain portion of liquid from the vapor, causing a certain portion of the vapor in said chamber and under relatively high compression to become suddenly expanded in a relatively large chamber to thereby suddenly reduce the pressure and cause intense 125

120

115

130

cold within the chamber, and conducting the remainder of the vapor from said accumulator chamber through said cooler chamber to thereby cause the condensation 5 of the gas.

2. In the art of producing gasoline and other light oils from vapor, a step which consists in passing the vapor under compression into a cooled separating or collecting tank to thereby condense a certain portion of the vapor, withdrawing a certain portion of the vapor and liquid from this tank, and suddenly expanding it in a chamber to produce an intense cold in the chamber, 10 conducting the remainder of the vapor through said chamber to thereby cool and condense said conducted vapor and discharging the product into an accumulating tank and recompressing the expanded vapor 15 from said cooling chamber and discharging it into said collecting tank.

3. An apparatus for the production of gasoline and other light oils from natural gas or other vapor including an accumulating tank, a compressor, means for conducting gas from the compressor into the accumulating tank, a cooler comprising a relatively large chamber into which compressed gas is conducted from said accumulating 20 tank, a stock tank connected to a source of vacuum, a pipe leading from the cooler into said stock tank, a pipe leading from the accumulator tank into the cooler and passing in a circuitous course through the cooler and 25 out of the same, a second accumulating tank into which the last named pipe discharges, 30

and means for conducting the condensed gasoline from the second accumulator tank to the stock tank and for conducting away the dry vapors from said second named 40 accumulator tank.

4. An apparatus for the production of gasoline and other light oils from natural gas and other vapors including an accumulating tank, a compressor connected to a 45 source of gas and discharging compressed gas into the accumulator tank, a cooler comprising a relatively large chamber, a pipe leading from the lower portion of the accumulator tank into said cooler and having 50 a valve discharging the gas and gasoline under pressure into said chamber where it may expand, a stock tank, a pipe leading from the cooler and discharging into the stock tank a pipe leading from the stock 55 tank back to the inlet side of the compressor, a second accumulator tank, a cooling coil connected to the first accumulator tank to receive dry gas therefrom, a pipe into which the cooling coil discharges, said pipe 60 discharging into the second named accumulator tank, a pipe leading from the second accumulator tank to discharge dry gas therefrom, and a pipe for carrying liquefied gasoline from the second accumulator 65 tank into said stock tank.

In testimony whereof I hereunto affix my signature in the present of two witnesses.
